Certificate of Correction.

It is hereby certified that the assignee in Design Letters Patent No. 68,569, granted October 27, 1925, upon the application of John L. Flannery, of Chicago, Illinois, for a Design for a "Cabinet," was erroneously described and specified as "The Boge Needle Co.," whereas said assignee should have been described and specified as The Boye Needle Co., as shown by the records of assignments in this office; and that the said Letters Patent should be read with this correction therein that the same may conform to the record of the case in the Patent Office.

Signed and sealed this 8th day of December, A. D. 1925.

WM. A. KINNAN,
Acting Commissioner of Patents.

UNITED STATES PATENT OFFICE.

JOHN L. FLANNERY, OF CHICAGO, ILLINOIS, ASSIGNOR TO THE BOGE NEEDLE CO., OF CHICAGO, ILLINOIS, A CORPORATION OF ILLINOIS.

DESIGN FOR A CABINET.

Application filed July 30, 1924. Serial No. 10,321. Term of patent 7 years.

To all whom it may concern:

Be it known that I, JOHN L. FLANNERY, a citizen of the United States, residing at Chicago, county of Cook, and State of Illinois, have invented a new, original, and ornamental Design for a Cabinet, of which the following is a specification, reference being had to the accompanying drawing, forming a part hereof, in which—

I claim:

The ornamental design for a cabinet, as shown.

JOHN L. FLANNERY.
